COOKING GRILL DEVICE

Walter Kozol, Russell, Ill., assignor to Charmglow Manufacturing Co., Antioch, Ill., a corporation of Illinois

Filed Feb. 19, 1969, Ser. No. 15,828

Term of patent 14 years

Int. Cl. D7—04

U.S. Cl. D81—10

The broken line showing of a support pole in all of the figures is for illustrative purposes only.

What is claimed is:

The ornamental design of a cooking grill device, substantially as shown and described.
